UNITED STATES PATENT OFFICE.

PAUL W. WEBSTER, OF PELHAM MANOR, NEW YORK, ASSIGNOR TO PERRY & WEBSTER INCORPORATED, OF ELIZABETH, NEW JERSEY, A CORPORATION OF NEW JERSEY.

PROCESS OF AND APPARATUS FOR TREATING VAPOROUS AND GASEOUS CONSTITUENTS OF FATTY OILS, GUMS, RESINS, AND LIKE MATERIAL.

Application filed January 16, 1920. Serial No. 351,825.

To all whom it may concern:

Be it known that I, PAUL W. WEBSTER, a citizen of the United States, residing at Pelham Manor, in the county of Westchester 5 and State of New York, have invented a certain new and useful Process of and Apparatus for Treating Vaporous and Gaseous Constituents of Fatty Oils, Gums, Resins, and like Material, of which the following is 10 a specification.

This invention relates to a process of and apparatus for treating vaporous and gaseous constituents of fatty oils, gums, resins and like material which are evolved during processes of manufacture.

In the manufacture of many kinds of varnishes, paints, lacquers, etc., drying oils such as linseed oil, tung oil, china wood oil, soya bean oil and various types of gums and 20 resins are heated and boiled. In these heating operations, fumes are driven off which consist of vapors of volatile oils and some comparatively permanent gases. These fumes have been a source of great annoyance to the manufacturers because they are 25 very obnoxious and form objectionable and dangerously inflammable deposits upon surfaces with which they come in contact while in concentrated condition, as for instance, 30 the interior surfaces of hoods, flues, stacks, etc.

In the boiling of oils and in the manufacture of varnishes and similar products, it is and has been the practice to cook the 35 oils, gums, etc. in kettles over open furnaces burning coke, fuel oil or other similar fuels. The products of combustion, together with the kettle fumes, have been led into special stacks and the high temperatures used and 40 flames thus present at the kettles increase the fire risk. Further, there is an ever present danger of the inflammable contents of the kettle catching fire, and as a matter of fact, kettle-flashing is of common occurrence.

45 Because of the above conditions, it has been the practice and has generally been considered necessary to sacrifice economy of ground area and economy of building construction and economy of operation by isolating the oil-boiling or kettle house with 50 its stacks from all the other buildings of a paint or varnish plant, and also to isolate, for instance, the process of cooking varnish from all the other processes of varnish man-

ufacture, such as the storage of gums, oils, 55 etc., the thinning, filtering and aging of the product, and the storage and packing and shipping of the product.

The design and construction of the kettle house and of its stack has moreover conformed to the necessity of its survival and 60 ability to withstand conflagrations and has been a one-story massive building, expensive to build and awkward and expensive for its 65 operation, as compared with, for instance, the design and construction of a modern 70 multi-story paint factory, where low investment cost and high efficiency of operation are obtained by use of modern structural building materials and design, and by storage of solid and liquid raw materials above 75 the floors for product production.

Varnish manufacture is analogous to paint manufacture and the two industries are closely related and much of the product 75 of a varnish factory becomes the raw material of a paint factory and many of the liquid raw materials are identical to both products.

One object of the present invention is to 80 provide a process of treating fumes formed in the manufacture of paints, varnishes, lacquers and the like, by which the obnoxious features of the fumes may be done away with.

Another object of the invention is to provide an apparatus for treating fumes formed in the manufacture of varnishes, paints, lacquers and the like, by which the danger and inconvenience of fires and explosions may be 90 effectively eliminated so that the treating operation may be carried on in buildings of the most advantageous type.

Extended investigation and experimentation with the fumes mentioned above has 95 shown that the fumes are composed of constituents which may be classified as follows, namely: partial condensates, intermediate condensates, end products, and permanent gases. The partial condensate is that portion of the fume which may be recovered by condensation at a moderate cooling temperature which may be generally defined as atmospheric temperature. The intermediate condensate is that portion of the fume which may be recovered by means of a liquid scrubbing operation. The end product is that 105 portion of the fume which is not controllable

and may only be recovered by a chemical treatment. The permanent gas is that portion of the fume which is not recoverable by condensation and chemical treatment and is 5 a product which has no marketable value. The partial condensate and intermediate condensate may be recovered with the end product by a chemical treatment. Also, the partial condensate may be recovered with the 10 intermediate condensate by a liquid scrubbing operation. The end product, however, cannot be recovered by a surface condensation or by a liquid scrubbing operation. Further, the intermediate condensate can- 15 not all be recovered by surface condensation at a moderate temperature. The partial condensate, intermediate condensate and end products defined above, have been found to be valuable oils, gums or products there- 20 of. Each of these products have different chemical characteristics as well as different physical properties.

Accordingly, a further object of the invention is to provide a process by which the 25 constituents of fumes formed in the manufacture of paints, varnishes, lacquers and the like, may be completely recovered as valuable by-products.

Another object of the invention is to pro- 30 vide a process of treating fumes formed in the manufacture of varnishes, paints, lacquers and the like by which the various constituents of the fume may be selectively recovered.

With these and other objects in view, the invention consists in the improved process 35 of and apparatus for treating organic fumes hereinafter described and claimed.

While I have shown a form of construction 40 and arrangement of apparatus which is preferred by me, it is obvious that either may be widely varied without departing from the spirit and scope thereof.

The various features of the invention are 45 illustrated in the accompanying drawings, in which,—

Figure 1 is a view in side elevation, of a fume-treating apparatus embodying the preferred form of the invention;

Fig. 2 is a plan view of the fume-absorbing apparatus shown in Fig. 1;

Fig. 3 is a vertical sectional view of the fire-arresting device;

Fig. 4 is a sectional view showing the 55 method of connecting the annulus to the kettle cover; and

Fig. 5 is a longitudinal sectional view of the chemical treating tank.

In the illustrated embodiment of the in- 60 vention, an apparatus is shown which is adapted for treating the fumes driven off from the heating kettles of paint, oil, and varnish factories. The paint, varnish or lacquer is heated or boiled in treating kettles 65 10, and the fumes evolved are carried off

through a collecting flue 12 and pass through a conduit 14 to a fire-arresting device 16. From the fire-arresting device, the fumes pass through a surface condensing conduit 18 into a condensate collector 20 which also 70 acts as a surface condenser for condensing the fumes at a moderate atmospheric temperature. The fumes leaving the collector 20 pass through the low temperature surface condenser 22 to a liquid scrubbing con- 75 denser 24. The circulation of the fumes through the apparatus described above is effected by means of a suction which is created by a positive pressure blower 26. The fumes passing through the blower 26 80 flow through a conduit 28 into a chemical absorption treating tank 30 where they are scrubbed and treated with an alkaline solution, and any unabsorbed vapors or gases leave the chemical treating tank through a 85 stack 32.

To effectively collect the fumes driven off from the kettles 10, a kettle cover 34 is secured at the lower end of the conduit 12. The various types of paint, varnish and lac- 90 quer-treating kettles have different sizes and shapes and it is desirable that the cover should make a comparatively close fit over the top of the kettle. To this end the cover 32 is made adjustable horizontally and ver- 95 tically to adapt itself for different kinds of kettles and to arrange for different positions of the kettle. The vertical adjustment of the kettle cover is obtained by means of a telescopic section 36 in the flue 12 and the 100 sections may be maintained in any desired vertical position by means of the cords 38 and weights 40. The horizontal adjustment of the cover may be effected by means of a ball and socket joint 41 formed at the 105 lower end of the flue 12, and a horizontal pivotal movement of the upper end of the flue 12. To permit the flue 12 to swing about a horizontal pivot at its upper end, a thimble 42 is secured to the upper end of the flue 110 12 and arranged to loosely fit over the end of the conduit 14. Opposite the thimble 42, a trunnion 44 is secured to the flue 12 and journaled in a bearing 47. With the construc- 115 tion outlined above, it is obvious that the cover may be adjusted horizontally into the positions shown in Fig. 1 and to different vertical heights.

For heating kettles having varying sizes of cross-sectional areas, the cross-sectional 120 area of the cover 34 may be contracted or expanded to adapt it for use with a kettle of substantially any cross-sectional area. To accomplish this, an annulus 46 of any de- 125 sired width and having an inner diameter substantially equal to the outer diameter of the cover 34 is arranged to be secured to the cover. To make a tight joint between the cover and the annulus, an inwardly pro- 130 jecting flange 48 is secured to the annulus

and arranged to project under the outer rim of the cover. When the flange 48 is mounted under the outer rim of the cover, it may be drawn tightly into place by means of pins 50 which pass through openings formed in upwardly projecting flanges 52 and 54 secured respectively to the annulus and cover.

The fumes driven off from organic fatty materials of animal or vegetable origin contain some constituents, which, when mixed with sufficient air, will ignite at comparatively low temperatures. When working with kettles heated by direct fire, these fumes are often ignited and the flames pass rapidly through the various flues and conduits for conducting the fumes through the treating apparatus. To prevent the flame from passing through the treating apparatus to come into contact with any condensed material, a flame-arresting device 16 is placed between the conduits 14 and 18. The flame-arresting device is shown more particularly in Fig. 3 and consists of a metallic container 56 which is secured to the conduits 14 and 18 and is in open communication therewith. In the body of the flame-arresting device is mounted a pair of fine mesh screens 58 which have such a texture that they will permit the fumes to pass therethrough but will prevent the flame from passing therethrough. The screens 58 are loosely mounted in the container 56 and a cover 60 provided at the upper end of the container by 35 which the screens may be easily removed for cleaning.

If the flame runs up the conduit 12 through the flue 14 to the fire-arresting device, there is a liability of an explosion in the flues if 40 they are too tightly closed. To prevent an explosion in the flues, an explosion door 62 is loosely mounted on the upper end of the flue 12.

The major portion of the partial condensates is recovered in the flue 18 and collector 20. To insure, however, that all of this condensate may be recovered, a cooling liquid may be circulated through the condenser 22 to insure that the fumes may be cooled to a sufficient degree to recover the partial condensates. Further, by using artificial cooling means in the condenser 22, part of the intermediate condensates may be recovered. Also, in the winter months, temperatures 55 sufficiently low for collecting the partial condensates and part of the intermediate condensates may be maintained in the condenser 22 without the circulation of a cooling liquid. The lower the temperature maintained in the condenser 22, the greater is the proportion of vapors condensed, but it is not practicable to use temperatures too low since the condensates recovered with low temperatures are quite volatile and it is preferred 60 to remove the more volatile constituents by

means of the jet condenser and chemical treatment.

The character and quality of the products recovered in the condensers 18 and 22 may be controlled also by oxidizing the fume 70 leaving the kettle. By means of the telescopic joint 36 in the flue 12, the proximity of the cover 34 to the top of the kettle may be adjusted to permit sufficient air to enter the flue 12 immediately over the kettle to 75 obtain any desired oxidation of the hot vapors leaving the kettle. If linseed oil is being treated in the kettle 10 and the fumes are oxidized, a distillate is recovered in the condensers 20 and 22 which has been termed 80 "linoxenated oil." This oil distillate has a lower boiling point than linseed oil and is well adapted for use in the flotation process for recovering metals and for other purposes. The linoxenated oil product is not 85 claimed in this application but forms the subject matter of my co-pending application for "Oxidizable oils," Ser. No. 256,738, filed October 3, 1918.

Although it is preferable to use a low 90 temperature condenser for separating a portion of the fume in the condenser 22, this is not always necessary since a large proportion of the vapors may be condensed with the ordinary type of water condenser. With 95 certain types of gums and resins, it is preferred to use an artificially cooled condenser since the proportion of condensable material recovered by atmospheric condensation is comparatively small. Also, in some of the 100 winter months, the atmospheric temperatures are sufficiently low so that it is not necessary to use a cooling medium.

For the complete control and removal of the intermediate condensates, jet condensing 105 or scrubbing is used by which the fumes are brought into direct contact with a spray of water which is introduced through a spray nozzle 64. Many different forms of jet condensers may be used, it being sufficient if 110 all of the gas is brought into intimate contact with a scrubbing liquid.

The obnoxious portion of the fume appears to be a comparatively permanent gas which is not separated by condensation or 115 water scrubbing. This portion of the fume, together with any uncondensed vapors, is removed by an alkaline solution in the treatment tank 30. The treatment tank 30 consists of a closed tank into which the fumes are introduced by a conduit 64 to a U-shaped manifold 66 positioned in the central portion of the tank near the bottom. The upper side of the manifold 66 is covered with a foraminated plate 68 by which the gas is thoroughly distributed through the alkaline solution. The alkaline solution may be continuously introduced into the treatment tank 30 and continuously withdrawn through an outlet 70.

A large number of organic fatty materials of animal or vegetable origin when heated or blown give off a fume which is very obnoxious and I have discovered that these 5 obnoxious ingredients may be reacted upon an alkaline solution, for instance, a solution of sodium hydroxide. Other alkalies such as lime, barium, hydroxide and potassium hydroxide may be used for treating the 10 fume, but the treatment with these alkalies is not quite as satisfactory as with sodium hydroxide. The fume of the organic fatty materials reacts with the alkaline solution by a reaction called saponification, and this 15 saponification product may be treated in turn to produce other products of commercial value.

By the terms alkali, or alkaline, in the 20 claims, it is intended to include both alkalies proper and alkaline earths.

By means of the process and apparatus outlined above, the various constituents of the fumes may be selectively and separately collected. The partial condensate may be 25 withdrawn from the collector 20 through an outlet 72, the intermediate condensate may be withdrawn from the scrubber 24 through an outlet 74, and the end products may be withdrawn from the chemical treatment tank through the outlet 70. If desired, the oil products recovered in the separator 20 and scrubber 24 may be blended together to form a single product, but the material recovered from the treatment tank 30 is a 30 saponification product or a soap, and it is desired, therefore, to recover the constituents as oils rather than in the form of a soap. Also, it may be desirable to collect fumes from the treatment of oils with a conduit having a low temperature condenser 35 in order to recover a higher percentage of linzenated oil products or derivatives therefrom, while on the other hand, the fume evolved from the treatment of materials containing gums, resins and the like may be subjected to jet condensation or scrubbing.

The subject matter of the present invention forms a continuation in part of my co-pending application, Serial No. 256,739, 50 filed October 3, 1918, for a "process of and apparatus for treating volatile constituents of fatty oils."

Having thus described the preferred form 55 of the invention, what is claimed as new is:

1. A process which comprises collecting fumes formed by treating products containing linsed oil, and chemically scrubbing the fumes with an alkaline solution.

2. A process which comprises collecting 60 fumes formed by treating fatty organic vegetable or animal material, oxidizing said fume, and condensing the oxidized fume.

3. A process which comprises collecting fumes evolved by heating a fatty organic 65 vegetable or animal material, oxidizing the

fume, separating a portion of said fume by surface condensation, and scrubbing the uncondensed fume with an alkaline solution.

4. A process which comprises collecting fumes evolved by heating a fatty organic 70 vegetable or animal material, separating a portion of said fume by surface condensation, separating a portion of said fume by scrubbing with water, and scrubbing the uncondensed fume with an alkaline solution. 75

5. A process which comprises collecting fumes evolved by heating fatty organic vegetable or animal material, and separately collecting a series of different constituents therefrom by fractional condensation. 80

6. A process which comprises collecting fumes evolved by heating fatty organic vegetable or fatty material and recovering from said fumes a series of different constituents separately and in succession by subjecting them to condensation and a scrubbing treatment with a chemically reacting absorbent. 85

7. A process which comprises collecting vapor fumes evolved by heating linseed oil 90 products, and scrubbing said fumes to separately remove oil condensates.

8. A process which comprises collecting fumes evolved by heating linseed oil products, and scrubbing said fumes with a water 95 spray to remove oil condensates.

9. An apparatus for treating fumes from organic fatty materials, comprising a fume collector arranged to be connected with a treatment receptacle, a fume condenser connected with said collector, a chemical treatment apparatus communicating with said condenser, and means for positively forcing fumes through the apparatus. 100

10. An apparatus for treating fumes from 105 organic fatty materials, comprising a fume collector arranged to be connected with a treatment receptacle, a fume condenser connected with said collector, a chemical treatment apparatus communicating with said condenser, means for positively forcing fumes through the apparatus, and means for preventing a flame from circulating through said apparatus. 110

11. An apparatus for treating fumes 115 evolved from organic fatty materials, comprising means for collecting fume from a treatment receptacle for said material, a chemical treatment apparatus, and means for conducting fume from the collector to 120 the chemical treatment apparatus having a flame arresting screen positioned therein.

12. An apparatus for treating fumes evolved by treating organic fatty materials, comprising a fume-collector, a surface-condenser communicating with said collector, a refrigerating-condenser communicating with said surface condenser, and means to prevent flames from passing through said apparatus. 125

13. An apparatus for treating fumes evolved by treating organic fatty materials, having in combination devices for treating the fume, conduits connecting said devices, a fume-collector connected with one of said conduits comprising a cover for a receptacle for treating organic materials, and means for varying the effective area of the cover.
14. An apparatus for treating fumes evolved by treating organic fatty materials, having in combination devices for treating the fume, conduits connecting said devices, a fume-collector connected with one of said conduits comprising a cover for a receptacle for treating organic materials, means for varying the affected area of the cover, and means for adjusting said cover vertically and horizontally.
15. An apparatus for treating fumes evolved by treating organic fatty material, having in combination devices for treating fumes, conduits connecting said devices, and a fume-collector connected with one of said conduits comprising a pivotally suspended conduit having a telescopic section therein and a receptacle cover secured to the lower end of said conduit.
16. An apparatus for treating fumes evolved by treating organic fatty material, having in combination devices for treating fumes, conduits connecting said devices, and a fume-collector connected with one of said conduits comprising a pivotally suspended conduit having a telescopic section and a movable section therein and a receptacle cover secured by the lower end of said conduit.
17. An apparatus for treating fumes evolved by treating organic fatty material, having in combination a fume-collector, a fume-condenser communicating with said collector, a condensate-collector communicating with said condenser, a chemical treatment apparatus communicating with said condenser, and an explosion door in said fume-collector.
18. An apparatus for treating inflammable fumes evolved by treating organic fatty materials, having in combination devices for treating fumes, conduits for connecting said devices, and a flame-arresting means in one of said conduits comprising a container having fine mesh screens therein and an explosion door.
19. An apparatus for treating fumes from organic fatty material, comprising a fume-collector arranged to be connected with a treatment receptacle, a fume-condenser connected with said collector, a liquid scrubber connected with said condenser, a chemical treatment apparatus communicating with said scrubber, and means for positively forcing fumes through said apparatus.

In testimony that I claim the foregoing, I have hereunto set my hand this 10th day of January, 1920.

PAUL W. WEBSTER.
